(57) **CLAIM**

The ornamental design for a watch as shown and described.

DESCRIPTION

Fig. 1.1 is a front view of a watch;
Fig. 1.2 is a rear view of the watch;
Fig. 1.3 is a right side view of the watch;
Fig. 1.4 is a left side view of the watch;
Fig. 1.5 is a bottom view of the watch;
Fig. 1.6 is a top view of the watch;
Fig. 1.7 is a perspective view of the front, bottom, and right side of the watch;
Fig. 1.8 is a perspective view of the front, bottom, and left side of the watch;
Fig. 1.9 is a perspective view of the rear, bottom, and left side of the watch; and
Fig. 1.10 is a perspective view of the rear, bottom, and right side of the watch.
The portions of the watch shown in broken lines form no part of the claimed design.
